[57] CLAIM

The ornamental design for a portable circular power saw support, substantially as shown and described.

DESCRIPTION

FIG. 1 is a perspective view of a portable circular power saw support showing our new design;
FIG. 2 is an enlarged front elevational view thereof;
FIG. 3 is an enlarged left side elevational view thereof;
FIG. 4 is an enlarged rear elevational view thereof;
FIG. 5 is an enlarged bottom plan view thereof;
FIG. 6 is a perspective view of a portable circular power saw support showing a second embodiment of our new design the sole difference being in the addition of the angle brackets as best shown in FIGS. 6, 8 and 9;
FIG. 7 is an enlarged front elevational view of FIG. 6;
FIG. 8 is an enlarged left side elevational view of FIG. 6;
FIG. 9 is an enlarged rear elevational view of FIG. 6;
and
FIG. 10 is an enlarged bottom plan view of FIG. 6.
